TANK REFRIGERATOR.
APPLICATION FILED JULY 26, 1920.

Patented Feb. 28, 1922.

2 SHEETS—SHEET 2.

UNITED STATES PATENT OFFICE.

HERBERT J. Gwyer, of YONKERS, NEW YORK.

TANK REFRIGERATOR.

1,407,857.

Specification of Letters Patent. Patented Feb. 28, 1922.

Application filed July 26, 1920. Serial No. 398,975.

To all whom it may concern:

Be it known that I, HERBERT J. Gwyer, a citizen of the United States of America, residing at 1 Leighton Ave., Yonkers, New York, have invented a new and useful Tank Refrigerator, of which the following is a specification.

My invention relates to a "knock-down" refrigerator construction.

10 It is an object of my invention to provide a refrigerator which may be made in knock-down parts which may be compactly packed for shipment.

15 It is a further object to provide a tank refrigerator having very simple and efficient means for supporting the tank within the cabinet.

20 It is a further object to construct an ice chamber of removable parts, said removable parts being of such size as to be stored in the water tank for shipment.

25 In general, it is the object to provide a very simple and efficient refrigerator which may be shipped in parts which are easily assembled.

Other objects will appear as specification proceeds.

30 My invention in its preferred form comprises a cabinet made up of six parts, namely, front and back units, side units, and top and bottom units. When assembled these units may be secured together by means of four bolts or rods passing from the top through the corner posts and through 35 the bottom. The corner posts are preferably secured to and form units with the front and back panels. A water tank is supported in the cabinet and is preferably secured between the front unit and the top. 40 Removable plates are provided for forming an ice chamber.

In the drawings which show merely preferred forms of my invention—

Fig. 1 is a fragmentary top plan view of 45 the refrigerator.

Fig. 2 is a front elevation thereof.

Fig. 3 is a vertical sectional view of the form shown in Fig. 2.

Fig. 4 is a fragmentary top plan view of 50 the construction shown in Fig. 3, but having the top removed.

Fig. 5 is a perspective view of the water tank and having a removable apron supported therefrom.

Fig. 6 is a modified form of construction shown in Fig. 3.

In said drawings, 5 indicates the front as a unit. 6-7 are the front corner posts. The panel member 8 is secured between the posts 6-7. Any suitable type of door such as 9 60 may be hinged to one of the corner posts and any suitable type of latch construction 10 may be provided for the door.

The corner posts as shown, particularly in Fig. 4, are preferably angular at the outer 65 side. In one of the inner sides of each corner post is a relatively shallow groove 11 and in the other inner side is a relatively deeper groove or hole 12. Between these grooves on the inside is preferably a beveled 70 projection 13 to provide a smooth inner surface for the cabinet. All of the corner posts are of the same cross-sectional shape. At the upper and lower ends of the corner posts are preferably provided upstanding projections 14 over which grooves in the top and bottom units fit for holding the cabinet together. 75

The top and bottom units are each made up of a frame having a panel secured therein 80 for the bottom unit, and having a door or lid hinged to the top unit. These top and bottom frames are each made up of parts such as 15-15 which are of substantially the same cross-section as the corner posts. Fitting in the grooves 16 of the top-unit are abutments or jams 17 for the lid. The lid or cover 18 may be of any desired or suitable construction. Fitting in the grooves 19 of the bottom unit is a panel 20. I prefer to 90 make all of the parts of my cabinet of thick, light wood such as ceiba or balsa wood, but it should however be understood that any suitable type of insulated walls might be provided if desired. Legs such as 21-21 95 may be provided for supporting the cabinet.

Each of the units is preferably covered with sheet metal both inside and outside. The corner posts, top and bottom frames, and abutments are all preferably metal covered. If desired, the door and lid may likewise be metal covered. As shown in the drawing, the edges of the metal are all turned in and secured between the various parts, whereby a smooth and attractive surface results. 100 105

Within the cabinet I support a suitable water tank 22. The tank is preferably pro-

yided with means, shown in the form of a flange 23, for supporting the tank. As shown particularly in Fig. 3, the flange 23 fits over the upper edge of the front unit and the top is then placed on the cabinet and securely holds the flange 23 in place. It will be noted that the beveled edge 24 fits over a part of the vertical wall of the tank, and the tank is thus securely held against displacement in any direction. After the tank has been secured in the cabinet any suitable type of faucet 25 may be screwed into the lower end of the tank and project outside the cabinet.

15 As shown in Fig. 3, a pan or tray 26 is provided for catching the drip from the ice. This tray may be supported at one edge on a ledge or projection 27 on the rear wall. At the front edge the tray may be supported from the tank. An apron 28 having a return bend 29 at the upper end is preferably hung from the upper edge of the tank. This apron 28 may be of corrugated metal or it may be of plain metal with a corrugated 25 plate 30 suitably secured thereto. The side edges of the apron may be provided with flanges 31—31 at opposite edges for a purpose to be later described. One edge of the tray 26 may be supported from the apron 28, but I prefer to provide a flange 31 on the lower end of the tank from which the tray 26 is supported. The edge of the tray as seen in Fig. 3 projects beneath the corrugated plate 30, so as to catch the drip or 30 condensation therefrom. A suitable aperture such as 32 may be provided in the tray to permit circulation of cool air. About the aperture is preferably an upstanding flange 33 to prevent water from leaking into the lower compartment of the refrigerator. The drain pipe 34 is provided for the tray.

At the back of the cabinet and preferably supported from the projection or ledge 27 is a plate 35. This plate may be provided 45 with channels 36 for a purpose to be herein-after described. Corrugated plates 37—38 may be provided for the sides or ends. The apron, tray, and plates constitute the ice chamber of my preferred construction.

50 After the tank has been secured in the cabinet, the tray or pan 26 may be placed therein. The apron 28 is next hung over the edge of the tank and the plate 35 placed in the back of the cabinet. The end plates 37—38 are next slid down the channels 36 which hold them at one edge and the flanges 31 hold the plates at the other edge. An ice rack 39 is preferably supported above the tray for supporting the ice.

60 In the modified construction shown in Fig. 6 the tray 26 is supported at the rear by a ledge 27, and at the front and adjacent the tank by a similar ledge or projection 40. In the form of construction shown in Fig. 65 any condensation or drip from the tank

or plates will be caught by the tray 26 and drained away. The apron, corrugated plates, tray, and removable legs are preferably of such dimensions that they will all fit in the water tank for shipment. It will be seen that all of the parts of my improved construction may be very compactly packed for shipment, and compactness is of very material moment in shipment, particularly 70 75 shipment by boat.

While I have described in great detail specific embodiments of my invention, I wish it to be understood that various modifications and changes may be made, all coming within the scope of the appended claims. 80

I claim:—

1. In a construction of the character described, a cabinet having a removable top, a tank having means thereon for supporting said tank in said cabinet, and said top 85 serving to hold said means in place.

2. In a construction such as set forth in claim 1, and a faucet leading from said tank to the exterior of said cabinet.

3. In a construction of the character described, a cabinet, a tank having a flange at the upper end fitting over one edge of said cabinet for supporting the tank therein, and a grooved top fitting over the upper end of said cabinet and serving to hold said flange 95 in place.

4. In a construction of the character described, a cabinet having a tank therein, a tray supported at one edge at one side of said cabinet and at another edge adjacent 100 said tank and corrugated plates supported in said cabinet and above said tray for forming the ice chamber.

5. In a construction of the character described, a cabinet having a tank supported 105 therein, a tray in said cabinet and supported at one edge at one side of said cabinet, and means carried by said tank for supporting the other edge of said tray.

6. In a construction of the character described, a cabinet having a tank supported therein, a tray in said cabinet and supported at one edge at one side of said cabinet, and a flange on said tank for supporting the other edge of said tray.

7. In a construction of the character described, a cabinet, a tank supported in said cabinet, an apron having a corrugated portion supported from the upper end of said tank, a tray supported adjacent the lower 120 end of said tank and corrugated plates in said tank, and forming with said apron and tray an ice chamber.

8. In a construction of the character described, a cabinet, a tank supported in said 125 cabinet adjacent the front side, an ice rack supported in said cabinet adjacent the lower end of said tank, an apron supported from said tank, a corrugated plate supported at the back side of said cabinet, side plates fit- 130

- ting between said apron and corrugated plate, and means on said plates and apron for holding them in position to form an ice chamber.
- 5 9. In a construction of the character described, a cabinet, a tank supported therein, removable plates in said cabinet for forming an ice chamber, said plates being of such size as to fit in said tank for shipment.
- 10 10. In a knock-down refrigerator, top and bottom units, four side units, all adapted to be secured together to form a cabinet, having means adapted to be held between said top unit and one of said side units to support the tank in the cabinet, and removable plates in said cabinet for forming an ice chamber.
11. In a knock-down refrigerator, top and bottom units, four side units, all adapted to be secured together to form a cabinet, removable legs for said cabinet, a tank removably supported in said cabinet, plates removably supported in said cabinet for forming an ice chamber, said legs and plates being of a size to fit in said tank for shipment.

HERBERT J. GWYER.
